RECORD REPRODUCING SYSTEM

Chester M. Sinnett, Westmont, and Rene Snep-vangers, Haddon Heights, N. J., assignors to Radio Corporation of America, a corporation of Delaware

Application November 17, 1942, Serial No. 465,852

16 Claims. (Cl. 179—100.4)

Our present invention relates to sound record reproducers, and more particularly to a phonograph system which does not employ a conventional form of tone arm.

In the past, sound records have been reproduced by placing the record on a motor-driven turntable, there being operatively associated with the turntable an electrical pickup device supported by a so-called "tone" arm. The pickup device is usually provided with a finely-pointed stylus, or needle, which rides in the record grooves. Various types of pickup devices have been used, viz; magnetic, crystal, capacity. Various electrical networks have been used to amplify the electrical voltage output of the pickup. For example, in a co-pending application of C. M. Sinnett (Serial No. 459,375, filed September 23, 1942) there is shown a system wherein the pickup device is capacitative, and acts to frequency modulate a high frequency oscillator in accordance with pickup capacity variations. In the Sinnett system the frequency modulated oscillations are detected by a simple form of off-tune diode rectifier.

The design of the pickup support arm is complex. Typical arms are provided with two pivoting points. The entire mechanical system of the arm must be carefully designed, as the pickup must be supported without adding pressure on the groove. Furthermore, it is practically impossible to eliminate swinging and torsional tone arm resonances in conventional tone arms. Hence, elimination of the conventional form of pickup support arm would obviate the need for solving such mechanical design problems.

Accordingly, it is one of the main objects of our present invention to provide a phonograph record playback system wherein a "tone" arm, or pickup support arm, is completely eliminated, and the pickup device of our invention being characterized by its being entirely supported by the record disc.

Another important object of our invention is to improve phonograph record playback systems by eliminating the conventional form of tone arm, and employing an ultra-high frequency oscillator in a circuit for converting small capacity changes, corresponding to motional displacements of a stylus, into audio frequency voltages.

Yet another object of our invention is to provide record reproducing equipment which consists essentially of a pickup and supporting means connected with a voltage utilizing network by means of a pair of twisted transmission lines whereby the pickup is limited in motion by the

lines so that when the pickup unit is placed on the record it functions in the normal manner to trace accurately the modulated record grooves.

Still other objects of our invention are to improve generally the simplicity and efficiency of pickup devices for phonograph record reproducer apparatus, and more especially to provide such devices in a reliable and economical manner.

The novel features which we believe to be characteristic of our invention are set forth with particularity in the appended claims; the invention itself, however, as to both its organization and method will best be understood by reference to the following description taken in connection with the drawing in which we have indicated diagrammatically a circuit organization whereby our invention may be carried into effect.

In the drawing, wherein Fig. 1 shows the pickup device resting on the record prior to playing, and Fig. 2 shows in plan view the positioning of the pickup device upon rotation of the record, we have shown one embodiment of our invention wherein the usual and conventional motor-driven turntable is schematically represented. On the turntable is shown a phonograph record 1 of any customary type; the manner of cutting of the record grooves is not important to the present invention. The pickup itself may be of any well known type. Where the electrical voltage, provided by the mechanical motion of the finely-pointed stylus riding in the record groove, is to be amplified by the use of the aforementioned Sinnett system, the pickup device may be of the capacity type. Of course, the pickup may be of the magnetic or crystal types if desired. In the latter case the pickup output could feed directly into a normal audio amplification system.

In the present application let it be assumed that the pickup unit is designated schematically by numeral 2, and that it is inserted within a circular opening provided in the support 3. The pickup unit 2 may be constructed in accordance with the teachings of C. M. Sinnett in application Serial No. 414,305, filed October 9, 1941. In general, such a pickup unit consists of a finely-pointed stylus, or needle, 4, which rides in the grooves provided in the face of the record. The element 4 may also be said to scan the record. In actual construction the stylus 4 is one plate of a condenser of small size. The fixed plate of the condenser is spaced within unit 2 from the stylus electrode, and the movable electrode may take the form of a metallic ribbon. The numeral 5 denotes the fixed or "hot" plate, and 6 the stylus attached to the movable ribbon. It is not neces-

5

dary to have the pickup unit 2 inserted within the support 3, as the pickup unit 2 may be attached directly to the record 1.

sary to show the details of the pickup unit interior, since the last mentioned Sinnott application clearly discloses the constructional details. Furthermore, since the present invention is independent of the specific construction of the pickup unit, the details of the latter are omitted.

Instead of using a conventional tone arm, and its finely-balanced construction, the supporting means 3 is utilized in place thereof. This support 3 generally is a metallic mass which may have any desired configuration. Specifically, and merely by way of illustration, the shape of the support 3 is shown as being substantially L-shaped. The L-shaped support 3 is preferably thin relative to its width. The lower face of the section 6 is provided with a member 7 which is in direct contact with the record face. The member 7 is preferably composed of a fibrous material, such as felt, which functions to pull the entire pickup and support along thus allowing the stylus 4 to trace the modulated grooves accurately. The felt pad 7 may have the shape of section 6. The felt pad will not tend to grip the record face, because the weight of the support is distributed over the large surface of the pad. Its thickness should be such that when the stylus point is positioned in a groove the lower face of the pad will contact the record face at all points.

The metallic support 3 can be of any metallic composition. We have found brass or copper to be most suitable. However, the mass of the support should be sufficient to act as a weight on the stylus such that proper pressure is exerted thereon. A minimum force of about 12 grams should be exerted on the stylus so as to prevent "skating" along the wall of the groove. A maximum force of about 1 ounce stylus force is sufficient to secure several hundred playings. The support weight, in general, should be so chosen that its vertical inertia is low so that it can follow an uneven record surface. Its horizontal inertia should be sufficiently low to minimize pressure on the groove sidewall and to avoid groove jumping, but not so low as to allow low frequency vibrations to be set up. Of course, materials may be used which are different from those disclosed herein. It will be noted that the present system has the advantage of eliminating swinging and torsional tone arm resonances, which are practically impossible to eliminate with conventional tone arms.

The tangential motion of the support is restricted by a pair of twisted conductors 8 and 9. One end of the conductor 8 is connected to the support 3, while the opposite end is connected to one terminal 8' of a tuned link circuit. The latter consists of coil 10 in shunt with condenser 11. The coil 10 has but a single loop, since the operating frequency may be chosen from a range of 100 to 500 megacycles (mc.). The stylus 4 is to be understood as being in electrical contact with the support 3 whereby the stylus electrode is electrically connected to terminal 8'. The second conductor 9 has one end thereof connected to fixed electrode 5 of the pickup, while its opposite end is connected to terminal 8' of tuned circuit 10-11. The conductors 8 and 9 may be a pair of twisted insulated wires. They are looped about a supporting post 12 so that tangential motion of the support 3 is restricted. Preferably, the transmission lines 8-9 are composed of fine wires.

The ultra-high frequency oscillations are provided by an oscillator circuit which comprises the tube 13 which acts as the oscillator tube. The

tube 13 may be a triode of the 6J5 type. The circuit shown operatively connected to 13 is well known, and is employed to generate ultra-high frequency oscillations. The resonant tank circuit comprises an inductance 14 which consists of a single loop. One end of the loop is connected to the plate 15, while the other end of the loop is connected to grid 16 through the direct current blocking condenser 17. The midpoint of loop 14 is connected to the +B terminal of the direct current energizing source, while the cathode 18 is grounded. The grid side of condenser 17 is connected to ground through grid leak resistor 19. The inductance of wire 14 is resonated by the distributed capacity thereof to the operating frequency of the oscillations. Other mechanical arrangements such as plates, cups, etc., may be used for the U. H. F. (ultra high frequency) resonant circuits as may be common in U. H. F., or micro-wave work.

While a frequency of 200 mc. can be used as an example, it is to be clearly understood that any other frequency in the stated megacycle range may be employed. For example, frequencies as high as 2,000 mc. may be utilized. Oscillator circuits for generating such high frequencies are known. It will be understood that the oscillator circuit generates the ultra-high frequency oscillations with substantially constant amplitude. If a crystal, or magnetic, pickup were used, the leads 8 and 9 could go to an audio amplifier.

There is located within the field of the oscillator tank circuit 14 a resonant circuit which comprises a loop conductor 20 shunted by a tuning condenser 21. Of course, the distributed capacity of conductor 20 may be employed to resonate conductor 20. The resonant frequency of circuit 20-21 is chosen so that it is located above or below the normal frequency of tank circuit 14. For example, circuit 20-21 may be tuned to 70% (approx.) of resonance. In other words, the resonant circuit 20-21 is mistuned with respect to the frequency of the oscillations generated by the oscillator circuit. The circuit 11-10, tuned to the frequency of circuit 14, is coupled to circuit 20-21, and will transfer to the latter any ultra-high frequency energy which exists in circuit 10-11.

Since the capacity of the pickup is across the circuit 10-11, variations in the capacity magnitude of the pickup will vary the frequency of the tuned link circuit in accordance with the modulation sound grooves of the record. In other words the recorded sound waves are converted into capacity variations, and the latter are transformed into frequency variations of circuit 10-11. However, circuits 10-11 and 20-21 are in the field of the oscillatory energy radiated by the oscillator. Hence, the ultra-high frequency energy absorbed by circuit 10-11 is modulated in accordance with the frequency variations of that circuit.

It will, therefore, be seen that there is produced in circuit 10-11 modulated ultra-high frequency energy, and this modulation is in accordance with the sound waves which were recorded on the record. The diode rectifier 30 is provided to rectify the amplitude modulated signal energy appearing in circuit 20-21, and thus provide the audio voltage which is reproduced to produce the originally recorded sound waves.

The anode 31 of rectifier 30 is connected to one terminal of condenser 21, while the cathode 32 is connected to ground. The opposite terminal of the circuit 20-21 is connected to ground by a

load resistor 40, which is by-passed by condenser 41 for ultra-high radio frequencies. The audio voltage developed across resistor 40 may be transmitted to a following audio frequency amplifier through the coupling condenser 50.

In operation, when it is desired to play a record the operator picks up the support 3 to change his record, and then merely places the support upon the record face as shown in the drawing in Fig. 2. The stylus point is positioned at the customary peripheral groove, and the turn-table is actuated. It is to be understood that the present invention is also applicable to records played back from the inside to the periphery. It is, also, applicable to cylindrical records, or, in general, to any form of rotating record employing a sound groove. As the turntable revolves the record moves in the customary fashion relative to the stylus. By virtue of the restraining influence of wires 8-9 and the action of the pad 7 on the record face the pickup support 3 pulls the entire assembly along towards the axial area of the record, with the result that the stylus point traces the modulated grooves of the record accurately. Of course, the wires 8-9 should be sufficiently long to permit the support 3 to be displaced towards the innermost grooves of the record. Furthermore, there should not be developed sufficient friction between the wires and post 12 to prevent such radial motion of the pickup support.

Support 3 will move toward the center of the record, as shown by the dotted lines in Fig. 2, because post 12 is located in the right place; on the centerline traced between the inside and outside grooves of the record. Besides, wires 8 and 9 are of small cross section, and thus will not resist sidewise motion of the support. Due to the location of the supporting wires 8 and 9, the shape and location of the felt pad with respect to the stylus, and the rotation of the record, the support is maintained at all times in the correct position to properly track the sound groove. Once this position is assumed, with the record rotating, there is nothing to change it, and even if the support is twisted deliberately it will return to the correct position when released. A balance of the forces, set up by the record due to its rotation, is accomplished by properly distributing the weight of the support between the pad and the stylus.

While we have indicated and described a system for carrying our invention into effect, it will be apparent to one skilled in the art that our invention is by no means limited to the particular organization shown and described, but that many modifications may be made without departing from the scope of our invention, as set forth in the appended claims.

What we claim is:

1. In combination with a sound wave record of the disc type, a pickup device provided with a stylus adapted to ride in the record groove, and means for supporting said pickup, said supporting means being completely positioned on the record face and adapted to be supported by the record.

2. In combination with a sound wave record of the disc type, a pickup device provided with a stylus adapted to ride in the record groove, means for supporting said pickup, said supporting means being completely positioned on the record face and adapted to be supported by the record, said supporting means being provided with a fibrous pad over at least a portion of the

lower face thereof, said pad being in complete contact with the record face, means for deriving an audio voltage from the pickup output, and conductors connecting said pickup to said deriving means.

3. In combination with a phonograph record adapted to be rotated about an axial point, a pickup device constructed and arranged so as to be wholly supported on and by said record, a transmission line connected to said pickup device and functioning to restrain the motion thereof in a tangential direction, and a network coupled to said transmission line for amplifying the electrical energy representative of the recorded sound waves.

4. In combination with a phonograph record, means for rotating the record about a central point, a pickup device, a supporting means adapted to be supported wholly on the face of the record, said pickup device being rigidly secured to said supporting means, and a flexible conductor connected between said pickup device and a point fixedly located relative to the record for constraining the motion of the pickup supporting means to radial displacement.

5. In combination with a rotatable sound wave record, a pickup device provided with a stylus adapted to ride in the record groove, means for supporting said pickup, and said supporting means being completely positioned on the record face and adapted to be supported by the record.

6. In combination with a sound wave record, a pickup device provided with a stylus adapted to ride in the record groove, a metallic mass for supporting said pickup, said supporting mass being completely positioned on the record face and adapted to be supported by the record, said supporting mass being provided with a fibrous pad, and said pad being in contact with the record face.

7. In combination with a phonograph record adapted to be rotated about an axial point, a pickup device constructed and arranged so as to be wholly supported on and by said record, a transmission line connected to said pickup device and functioning to restrain the motion thereof in a radial direction, and a network coupled to said transmission line for amplifying the electrical energy representative of the recorded sound waves.

8. In combination with a phonograph record, means for rotating the record, a pickup device, a supporting weight adapted to be carried wholly on the face of the record, said pickup device being rigidly secured to said supporting weight, and a flexible conductor connected between said pickup device and a point fixedly located relative to the record for constraining the motion of the pickup supporting weight to radial displacement.

9. In combination with a sound wave record of the disc type, a pickup device provided with a stylus adapted to ride in the record groove, and a metallic mass for supporting said pickup, said mass being completely positioned on the record face and adapted to be supported by the record, and flexible means to restrain the motion of the mass.

10. In combination with a sound wave record of the disc type, a pickup device provided with a stylus adapted to ride in the record groove, a weight for supporting said pickup, said weight being completely positioned on the record face and adapted to be supported by the record, said weight being provided with a fibrous pad over at least a portion of the lower face thereof, said

pad being in complete contact with the record face, means for deriving an audio voltage from the pickup output, and flexible conductors connecting said pickup to said deriving means.

11. In combination with a phonograph record adapted to be rotated about an axial point, a weighted pickup device constructed and arranged so as to be wholly supported on and by said record, a flexible transmission line connected to said pickup device and functioning to restrain the motion thereof in a radial direction, and a network coupled to said transmission line for amplifying the electrical energy representative of the recorded sound waves.

12. In combination with a phonograph record, means for rotating the record about a central point, a pickup device, a metallic plate adapted to be supported wholly on the face of the record, said pickup device being rigidly secured to said plate, the plate being provided with a fibrous pad in contact with the record face, and a flexible conductor being connected between said pickup device and a point fixedly located relative to the record for constraining the motion of the pickup supporting plate to radial displacement towards said central point.

13. In combination with a sound record of the type provided with grooves representative of sound signals, a pickup device provided with an element adapted to ride in the record grooves, means for supporting said pickup in operative relation to said record, and said supporting means being completely positioned on the record face and adapted to be supported by the record.

14. In combination with a rotatable sound record provided with signal-representative grooves, a pickup device provided with an element adapted to ride in the record grooves, means for supporting said pickup in operative relation to said record, and said supporting means being completely positioned on the record face and adapted to be supported by the record, the area of the supporting means for the pickup being a small fraction of the total area of the record.

15. In combination with a rotatable grooved sound wave record, a pickup device provided with an element adapted to ride the grooves of the record, means for supporting said pickup device, said supporting means being completely positioned on the record face, at least a portion of said supporting means being provided with an element in frictional contact with said record face.

16. In combination with a sound wave record provided with grooves, a pickup device provided with a needle element adapted to ride the grooves of the record, means for supporting said pickup device, said supporting means being completely positioned on the record face, at least a portion of said supporting means being provided with an element in frictional and sliding contact with said record face, and said last element having an area which is a small fraction of the total area of the record.

CHESTER M. SINNETT.
